UNITED STATES PATENT OFFICE.

JAMES H. BARLEY AND THOMAS K. BARLEY, OF SEDALIA, MISSOURI.

HAY-STACKER.

SPECIFICATION forming part of Letters Patent No. 355,119, dated December 28, 1886.

Application filed August 10, 1885. Serial No. 174,064. (No model.)

To all whom it may concern:

Be it known that we, JAMES H. BARLEY and THOMAS K. BARLEY, citizens of the United States, residing at Sedalia, in the county of 5 Pettis and State of Missouri, have invented a new and useful Improvement in Hay-Stackers, of which the following is a specification.

Our invention relates to an improved hay-stacker; and it consists in the novel features of 10 construction and combinations of parts herein-after described, and pointed out in the claims.

In the accompanying drawings, Figure 1 is an isometrical perspective view of our improved stacker with the fork or carriage nearly 15 down to a position for being loaded. Fig. 2 is a detail perspective view showing more completely the guide-rope for the draft-animal. Fig. 3 is a broken detail vertical section of part of Fig. 1, showing the fork in the 20 act of rising. Fig. 4 is a broken side elevation of part of Fig. 1, showing in full lines the fork fully raised and inclined, with its front end elevated, and also showing by dotted lines the dumping position of the fork. Fig. 5 is a 25 detail section of the foundation-support and the upright frame of the stacker. Fig. 6 is a sectional view similar to Fig. 3, but showing two elevating-ropes rove in a different manner from the single rope in Fig. 3. Fig. 7 is a 30 detail plan of the top pulley-beam and the ropes shown in Fig. 6. Fig. 8 is a modification of the construction of the upright frame shown in Fig. 1. In this view are shown by dotted lines inclined braces between the guiding-bar and top pulley-beam of the upright frame, which may or may not be used. Fig. 35 9 is a modification of the guide-rope shown in Figs. 1 and 2. Fig. 10 is a detail view showing a modification of the construction of the 40 side frame-pieces of the fork-handle; and Fig. 11 is a diagram illustrating the position of the 45 hay-stack being formed with respect to the upright frame and fork. Figs. 12, 13, and 14 show other modifications of the guiding device for the draft animal or animals.

In the drawings, A A' are oblique horizontal side sills, A² a front cross-beam uniting the sills, B B slide shoes or runners, and A⁴ an adjusting and bracing rear cross-bar of the 50 approximately V-shaped foundation-frame for a horizontally-swinging upright, C. The cross-

beam A² is bolted to the tops of the runners, and the sills are pivoted to it, while cross-bar A⁴ is perforated with a number of holes, a, and is confined to the tops of the sills by bolts a', as 55 shown. By means of the bar A⁴ and bolts and holes the pivoted side sills can be set to form a greater or less angle with each other, or, respectively, with the front cross-bar, according- 60 ing as circumstances may require.

The bar A⁴ may, while it serves as a stay or brace, also act to keep down in horizontal position a sweep-bar, K, arranged below it and attached by one end either to the foundation-frame or to the swinging upright, so as to 65 sweep in the arc of a circle, and thereby cause the upright with the fork to swing in a similar arc; but, if preferred, the sweep-bar may be kept horizontal by an inclined brace, A⁵, Figs. 1 and 8, which may be either loosely jointed 70 or rigidly connected to the part C of the upright frame and suitably connected to the sweep-bar.

Loops or staples may be provided at the front and rear of the foundation-frame, as 75 shown, for anchoring the stacker while in use. The upright C is connected to the cross-bar A² by a strong metal pivot-bolt, b, a nut, b', an iron washer, b², and a foot-plate, b³, as shown, or in any other suitable manner.

The nut b' might be dispensed with and an 80 ordinary step-bearing adopted.

The upright may comprise two pieces—one, C, forming the main portion or stacker-pole proper, and the other, C', the guiding-bar for 85 the hay-elevating fork D. The parts C and C' are set apart a proper distance, one vertical and the other preferably declining therefrom. Said parts may be rigidly united at bottom by a stout tie-piece, c², or by other suitable rigidly-connecting means, and rigidly at top by a pulley or roller-beam, C², or equivalent rigidly-connecting means. Said beam is shown set inclined to the horizon, and formed so as to enable the draft-animal to pull in a more direct 90 line between the points d and d' in lifting the weight, and it is shown formed of two flat bars, between which grooved pulleys or rollers d d', as well as the upper ends of the parts C C', are fitted and suitably secured. As indicated 95 in the drawings, the part C' stands away from the pole proper, C, either on a declining or

vertical line, but swings with it on the pivot b in an arc of a circle, as illustrated by the diagram, Fig. 11.

In Figs. 1, 3, 4, 5, and 6 the pole proper, C, is shown with its part C' on a declination from the perpendicular, and the pulley-beam C² set inclined to the horizon, so that its forward end is inclined upward; and we prefer generally to adopt this construction, as it affords greater room for employing an inclined brace, C³, permits the fork to move to a greater altitude and to be more conveniently tilted in topping off the stack, while it obviates the necessity of separating the lower ends of the parts C C' to an objectionable extent in order to introduce the brace between the said parts and the beam C².

In Fig. 8 we have shown a modification of the pivoted swinging upright, both of its parts being vertical.

The space between the parts C C' affords room for the inner end of the handle D' of the fork D to move up and down bar C' and vibrate in. The fork D is thus located away from the axis of motion of the stacker-pole C, and thrown, when swung around, nearer the center of the stack of hay being formed. The upright thus constructed and pivoted is steadied and stayed upon the foundation-frame by two inclined braces or props, E, which are connected by their upper convergent ends to the upper portion of the pole proper, C, by suitable loose joints, as e², and by their lower divergent ends to the sills A A' by a series of bolts, e, and holes e' in said sills. When the cross-bar A' is adjusted to hold the sills farther apart, the braces or props can be adjusted accordingly.

The fork D of the stacker comprises tines f, head-bars f' f², swinging lifting-bail f³, a locking-bar, h⁴, a pendent pivoted catch, h⁵, with dangling operating-cord h⁶ attached thereto, the handle D', having a latching device, h⁷, as a pin or a guiding-staple, and the cross-bar h⁸, hinged at i i to the head-bar f² of the fork, so as to permit the fork to tilt downward, as indicated by dotted lines in Fig. 4. The handle D' is formed of two horizontal spaced bars, g g, and two inclined spaced bars, h h, bolted together and to the spacing pieces or blocks h² h³. On the outside of the bars g g and h h, at their rear ends, tie-pieces h' may be applied.

Within the frame forming the handle anti-friction rollers j j² and a round spacing-block or friction-roller, j', are placed, and between the inclined bars h h, forward of said rollers or roller j', a grooved pulley, d³, is applied. The space between the side pieces of the handle D' forward of the roller j should be sufficient to permit the fork to be vibrated or tilted on its guide rod or bar C', and assume the position shown in Fig. 4, as in the case of topping off the stack. The rollers j j² bear, respectively, against the front and rear of the guide bar or rod of the pole, while the block or roller j' may move clear of the rear side of the said guide.

The fork is suspended and operated by the

rope-hoisting appliance F or F F', which may be rove in either the manner illustrated in Figs. 1, 3, and 4, or as in Figs. 6 and 7. If 7c rove as in Figs. 1, 3, and 4, the rope F is first attached to the swinging bail f³, carried over the front pulley, d, down to and under the pulley d³, up to and over the pulley d', and along the beam C², over the pulley d², therefrom down to a swinging draft pulley-block, d⁴, on the sweep-bar K, and thence to the draft-animal, as shown; but in the arrangement shown in Figs. 6 and 7 two ropes, F F', are used, the rope F being first fastened to 80 the front end of the beam C², carried down and under a pulley, d⁵, on bail f³, up over pulley d, along beam C², over pulleys d' d² to the draft pulley-block d⁴, and thence to the draft-animal, while the rope F' may be fastened to the beam: 85 C² near its center, carried down under the pulley d³, up to and over pulley d', over pulley d², down to the draft pulley-block d⁴, and thence to the draft-animal. By this means the fork with its load is lifted and held up at 90 a right angle with the guide-bar C', and binding prevented.

It is important to provide for passing the rope over a top pulley-beam, C², and over two or more pulleys, one of which is supported at 95 a point considerably forward of the guide-bar C', and another considerably in rear of the part C of the pole, as shown, as by this construction and arrangement the weight of the fork forward of the pole is counterbalanced by the draft of the team. The fork-head is allowed to dump by drawing the catch h⁵ backward from the staple or pin by the cord h⁶. The dumping of the fork may be effected at any altitude, and when the body of the stack has been completed and it 105 is desired to "top off," the roller j will travel up the inclined brace-bar C³, whereby the weight is in a measure removed from the catch and the front end of the fork thrown up, as illustrated in Fig. 4, and thus the load caused 110 to be dumped at a greater height than the body of the stack. In Figs. 1 and 3 we have shown, at C³*, by dotted lines, a duplication of the brace C³; and it is our intention sometimes to use two braces instead of one, in order to 115 give greater support to the pulley-beam C²; and the brace C³* is made of greater length than brace C³, as shown, so as to cause the lower front friction-roller, j², to travel upon said front inclined brace; and the friction 120 roller or block j' and roller j² may be placed a great distance apart, so as to permit the fork to tilt or rise at the front end when the handle rises on the brace C³*. It will be seen that this front brace would cause the front end of 125 the fork to rise in the same manner as brace C³, and hence brace C³ might be left off, if desired.

If desired, the side bars of the fork-handle might be extended back and the rear roller, j', left off, so as not to interfere with the front roller passing along brace C³*. If the brace C³* is used, the pulley d' would be set forward of it, the front end of beam C² extended, and

pulley d set forward. For controlling the draft animal or animals, an ordinary guiding device, as a rope or rail, H , (see Figs. 1, 2, 13, and 14,) is connected to a staple, H' , of one of the props or braces E , and extended to a stake, H^2 , set in the ground, as shown in Figs. 1 and 2. This rope or rail is arranged near the side sill, A , of the foundation-frame, so that the draft end of the rope F shall be carried on a line diagonal from the block d^4 to the point of attachment to the harness of the animal, and thereby the swinging of the upright in the arc of a circle insured and controlled, the rope or rail preventing the animal moving out of a straight line, and the pull of the animal on the draft end of the rope causing the sweep-bar, when it is unlatched, to move toward the guiding device, whether a rope or rail.

If the animal is not guided as we show, a driver must keep him in a straight path in order to insure a continuous movement, or prevent an irregular swinging movement, of the swinging upright in the arc of a circle for dumping the loaded fork. On this cable rope or rail an ordinary ring, H^3 , is fitted loosely, and connected by a chain or strap to a hook of the harness of the draft-animal, as illustrated. An ordinary backing-cord, H^4 , leading from a staple, H^5 , on the bar A' , is connected to the bridle of the draft-animal. By this ordinary guiding and backing arrangement of devices the animal will always be guided correctly, thus avoiding the expense of employing a driver, and by means of the cord H^4 he can be caused to back for a new start, and after the animal has been trained by this cord the cord may be dispensed with. A rope or rail on each side of the animal, as shown in Fig. 12, might be used, in which case it would not be necessary to connect the animal to the ropes; or, instead of the rope H , a traveling endless guide-rope might be arranged on two pulleys, H^6 , and the connecting-ring H^3 be fastened permanently to one part of the rope, as illustrated in Fig. 9. The guide-rope and controlling-cord may be used with a team as well as a single animal, as shown in Fig. 13, the rope being placed between the two animals as a guide.

For swinging the pole in an arc of a circle to dump the loaded fork, the sweep-bar K , pivoted to the beam A^2 , may have one end of a cord, I , fastened to it, while the other end of said cord is carried around a pulley, I' , on one of the sills $A A'$, and fastened by a perforated latch-plate, I^2 , to a pin, I^3 , on the other sill. By this arrangement the sweep-bar can be adjusted so as to stand near one of the sills of the foundation-frame while the animal is raising the loaded fork, and then, as soon as the load is raised, by pulling the plate I^2 off the pin I^3 by means of the loose end I^4 of the cord, the power of the draft-animal will cause the upright frame $C C'$ to swing around over the stack, and then by readjusting the bar K and the plate upon the pin I^3 and swinging back the fork by the hand-lever J , attached

to the lower part of the upright proper, or by other means, the operation of elevating and depositing the load upon the stack can be repeated.

What we claim as our invention is—

1. A hay-stacker comprising in its construction a pivoted swinging upright consisting of the part C and the laterally-placed rigidly-connected part C' , in combination with a hay-elevating fork, and means for hoisting said fork, substantially as and for the purpose described.

2. The combination, with the upright comprising pivoted pole C and the rigidly-connected guiding-bar C' , of a hay-elevating fork, and means, substantially as set forth, whereby it is guided up and down on the bar C' , substantially as and for the purpose described.

3. The combination of the upright, comprising a vertical pivoted pole, C , and an inclined guiding-bar, C' , rigidly connected to it at top and bottom, with a hay-elevating fork, and means, substantially as set forth, whereby it is guided up and down on the bar C' , substantially as and for the purpose described.

4. The combination of a base-frame, an upright pivoted at its lower end thereto, inclined props E , having their upper ends hinged to the upright, the top pulley-beam, C^2 , attached to the said upright, and supporting pulleys forward thereof, and a hay-elevating fork, with hoisting means, substantially as described, connected thereto, suspended on said pulley-beam, and means whereby its handle is guided up and down forward of said upright, substantially as and for the purpose described.

5. The combination of the upright, comprising pole C , pivoted at its lower end, and a rigidly-connected lateral guiding-bar, C' , two pulleys at the upper end of the upright, support for the pulleys, respectively, at points in rear and forward of the upright, a fork guided on the bar C' , and means, substantially as set forth, for raising the fork, substantially as and for the purpose described.

6. The combination of a pivoted upright having inclined props loosely connected to it, a pulley-support at the upper end thereof, two or more pulleys located on said support forward of the upright, an elevating-fork, and means for hoisting the fork and guiding it on said upright, substantially as and for the purpose described.

7. The combination, with a swinging upright and a fork guided by and forward of said upright, of two pulleys, support for said pulleys near the top and forward of the upright, and means, substantially as set forth, for hoisting the fork, connected at separate points forward of the upright—viz., to the fork-head and handle—substantially as and for the purpose described.

8. The combination, with a swinging upright comprising pivoted pole C , a rigidly-connected lateral guiding-bar, C' , a top pulley-beam, C^2 , and pulleys on the beam, of a hay-elevating fork guided on said bar, and a hoist-

ing-rope rove, as described, with respect to the pulleys of the beam, fork-head, and handle, substantially as and for the purpose described.

5 9. The upright provided with an inclined brace at its upper end, in combination with an elevating-fork having its handle formed with a space between its side portions, and devices adapted for bearing upon the said inclined brace during its ascent, and means for hoisting the fork, substantially as and for the purpose described.

10 10. The combination of the foundation-frame, comprising oblique side sills, A A', cross-beam A², and rear stay-bar, A⁴, a hay-stacker upright, inclined props E, elevating-fork D, guided on the upright, and means, substantially as set forth, for hoisting the fork, substantially as and for the purpose described.

15 11. The sweep-bar K and its draft pulley-block, in combination with pivoted upright, a top pulley-beam, C², the elevating-fork, and means, substantially as described, connected to the fork, passed over the pulley-beam and 20 through the draft pulley-block, substantially as and for the purpose described.

25 12. The combination of a pivoted upright, a fork guided by the bar C' of said upright, the hoisting means, substantially as described, 30 rove, as described, with respect to the fork, the pulleys supported at the top and in front and in rear of the upright, the sweep-bar K, and the draft pulley-block, substantially as described.

35 13. The combination, with the foundation-frame, the pivoted upright, the top beam thereof, the elevating-fork, the rope, pulleys attached to the top beam of the upright and to the fork-handle, of the sweep-bar K, and 40 the draft pulley-block on the outer end of the sweep-bar K, the cord I, connected to the

sweep-bar, and a latch, substantially as described.

14. The combination, with a swinging upright and a fork guided by and forward of 45 said upright, of two pulleys, support for said pulleys near the top and forward of the upright, and means for hoisting and guiding the fork forward of the upright, substantially as and for the purpose described. 50

15. The combination of the foundation-frame, a sweep-bar, K, a pulley, I', a cord, I, connected to said bar K and passing around the pulley I', an upright, an elevating-fork, a hoisting-rope, and pulleys, substantially as 55 described.

16. The fork, comprising tines, head-bars, handle, spacing and bearing devices, hinging-connections, latching-bar, pendent latch, and a latch-retaining device, in combination with 60 a pivoted upright and a hoisting-rope, substantially as and for the purpose described.

17. The combination, with a pivoted upright constructed with guiding-bar C', of the fork D, having its handle D' formed of spaced 65 horizontal bars g, embracing the guiding-bar C' of the upright, and inclined bars h, having their front ends connected with the forward ends of the bars g, and extended rearwardly, so as to embrace bar C', vertical bars for connecting rear ends of the side bars, friction-rollers bearing in front and rear of said bar C', and a hoisting-rope connected to the fork, 70 substantially as described.

In testimony whereof we affix our signatures 75 in presence of two witnesses.
